UNITED STATES PATENT OFFICE

NEAL T. MCKEE, OF BRONXVILLE, NEW YORK, ASSIGNOR TO AMERICAN THROTTLE COMPANY, INC., OF NEW YORK, N. Y.

LOCOMOTIVE

Application filed November 17, 1926. Serial No. 148,870.

My invention relates to locomotives and has particular reference to the boiler dry pipe and the steam controlling means in the steam line leading to the locomotive engines.

Heretofore locomotives have generally been equipped with throttle valves located within the steam dome of the boiler and with the steam pipe leading to the engine through the steam space of the boiler and the forward flue sheet thereof. This form of construction has made necessary the use of piping within the boiler capable of withstanding boiler pressure, as with the throttle in the steam dome closed the portion of the steam pipe lying within the steam space of the boiler is subjected externally to full boiler pressure.

In some recent forms of construction, the throttle valve has been placed outside of the boiler, and in cases where the locomotives have been equipped with superheaters, between the superheater and the engine cylinders. With the forms of outside throttle heretofore used, however, it has been necessary to place an emergency shut-off valve in the steam dome so that in case of a leaky throttle valve or the failure of some portion of the steam line or of some element in the superheater located between the steam outlet from the boiler and the throttle valve, the emergency valve in the dome may be used to shut off the steam supply from the boiler. One of the principal advantages of the outside throttle is its comparatively greater accessibility for maintenance and repair, but this advantage has not been fully realized in the forms heretofore employed because of the inaccessibility of the emergency shut-off valve used in conjunction with the outside throttle. Furthermore, in actual practice the emergency shut-off valves are not tested as frequently as they should be, and very frequently become so encrusted with deposits of scale as to become inoperative. The use of the emergency shut-off valve furthermore necessitates the use of piping within the boiler capable of withstanding boiler pressure, for the emergency valve when used produces a condition exactly the same as if the throttle valve were located in the dome and were closed, in which case the steam pipe

within the boiler would be subjected to full boiler pressure.

It is also desirable to provide the maximum accessibility to the interior of a locomotive boiler, and the steam dome provides an opening large enough for a man to enter the boiler except for the fact that the presence of the usual throttle or emergency valve obstructs this possible entrance to the boiler.

My invention has for its principal object the provision of apparatus which will enable the advantages of the outside throttle to be realized to their fullest extent by placing both the throttle valve and the emergency shut-off valve in an accessible position outside of the locomotive boiler. Another object of the invention is the provision of an improved form of steam dry pipe within the boiler which will be not only less expensive than the forms heretofore used, but which will in addition provide greater accessibility to the interior of the boiler by way of the steam dome, and which will in addition assure the delivery from the boiler of dry steam. Other and more specific objects of my invention as well as the advantages to be derived from the use thereof will appear more fully from the following detailed description of a preferred embodiment illustrated in the accompanying drawings in which Fig. 1 is a fragmentary vertical section through the smoke-box and forward end of the boiler of a locomotive to which my invention has been applied. Fig. 2 is a fragmentary section taken on the line 2—2 of Fig. 1. Fig. 3 is a section taken on the line 3—3 of Fig. 1. Fig. 4 is a horizontal section taken through the smoke-box of the locomotive with certain portions of the figure broken away for clearness, and Fig. 5 is a section taken on the line 5—5 of Fig. 4.

Referring now to Fig. 1, I have illustrated my improved construction as applied to a locomotive equipped with the usual form of fire tube superheater, in the header of which there is incorporated a multiple valve throttle of the general type shown in Reissue Patent No. 16,285 granted March 9th, 1926, to R. M. Brown, but it is to be understood that this specific form of valve construction is illustrative only and the invention is not

to be limited thereby. In the figure, the numeral 1 represents the main boiler sheet which is extended forward of the flue sheet 2 to form the smoke-box 3 in which is located the superheater comprising a header unit 5 formed by a saturated steam or inlet header 4, to which steam from the boiler is supplied from the boiler outlet 5, and a superheated steam or outlet header 6 from which superheated steam is delivered to the engine through the steam pipes 7. The headers 4 and 6 are each formed with interleaving fingers, from some of which saturated steam is delivered to the superheater units 8 located in flues 9, and to the others of which superheated steam is delivered from the superheater units.

The engine throttle valve comprises a plurality of small poppet valves 10 located in the outlet header 6 and arranged to be progressively opened by the throttle control rod 11 through the medium of the cam shaft 12. This form of construction is well-known and the details thereof need not be described further.

In accordance with my invention, the emergency shut-off valve required with this form of throttle is placed adjacent the steam outlet of the boiler so that it may act to shut off the steam from the entire steam line. As applied to the multiple throttle illustrated, the emergency shut-off valve comprises a plurality of small poppet valves 13 similar to the main throttle valves but distributed along the inlet header 4, which is divided into an upper steam inlet chamber 4^a in communication with the boiler outlet 5 and a lower chamber 4^b from which steam is distributed to the header fingers leading to the superheater units. As will be apparent from Fig. 1, the several valves 13 control a plurality of ports joining the two header compartments, and are so arranged that the normal action of the steam flowing through the header tends to force these valves to their closed position. In order to raise the valves 13 and permit steam to flow through the superheater to the main throttle valve, a cam shaft 14 is provided which carries a series of cam arms 14^a, each of which engages a suitable slot in one of the valves 13 so that rotation of the cam shaft by means of the control rod 15 serves to open these valves. The rod 15 is connected to any suitable form of operating lever equipped with a ratchet or equivalent mechanism (not shown) for holding it in fixed position, and this mechanism may be, if desired, located in the engine cab or may, if desired, be mounted on the boiler adjacent the operating shaft 14.

The operation of this emergency valve will be quite apparent, the several valves 13 being normally maintained in their open position by means of the cam shaft 14 to permit steam to pass through the superheater

and throttle to the engine. In the event of throttle or other leakage in the steam line, it is only necessary to release the mechanism holding the valves 13 in their open position, whereupon the unbalanced steam pressure on these valves forces them to their closed position and shuts off the steam supply to the engine steam line. In this connection, it is to be noted that by the use of valves of the type shown, the danger of their sticking in open position because of scale formation is reduced to a minimum because of the absence of sliding surfaces, and it is further to be noted that these valves will be forced to a seat by full boiler pressure.

In prior installations where outside throttles have been used in conjunction with emergency shut-off valves located in the steam dome, some form of safety valve has been required in the superheater in order to relieve excessive pressure which may be developed therein with both throttle and emergency valves closed, due to the evaporation of water which might have been carried over into the superheater. With a structure arranged in accordance with my invention, the necessity for a separate safety valve is eliminated by the provision of an auxiliary valve 13^a which is provided not only for the purpose of relieving excess pressure from the superheater, but also for the purpose of admitting steam to the superheater for balancing the valves 13. It will be obvious that the valves 13, once they are closed, must be opened against a very heavy pressure and in order to facilitate the opening of these valves against boiler pressure, the valve 13^a is provided having a slot therein in which the cam arm 14^b fits so that it is substantially in contact with the valve when the latter is seated. The slots in the stems of valves 13 provide a substantial clearance above the arms 14^a when the cam is in the closed position shown in the figure, so that when the operating shaft 14 is rotated to open the valve, the auxiliary valve 13^a is opened first. The opening of this valve admits steam into the superheater, which, if the main throttle is closed, forms a closed balancing chamber in which the pressure builds up to a point where the valves 13 are substantially balanced. After the balancing of these valves by steam pressure, the operating shaft 14 may be rotated with very little effort to open them. The stem of valve 13^a is slotted so that a substantial clearance exists between the bottom of the slot and the lower face of the cam arm 14^b, and in case excessive pressure for any reason develops in the superheater, this pressure will be automatically relieved by reverse flow through the valve 13^a into the boiler. Obviously, the stems of valves 13 may be slotted so that there is a clearance below the cam arms 14^a permitting these valves also to be

lifted slightly by excessive steam pressure in the superheater, but I prefer to use slots as shown in order that mechanical pressure may be exerted on the valves 13 to bring them to their seats. If desired, the valves 13 may be allowed to lift under the influence of steam pressure in the superheater by arranging the cam arms 14^a and 14^b and the slots which they respectively engage so that the arms 14^a may be lifted slightly above the lower edge of their slots before the arm 14^b contacts with the upper end of the slot in valve 13^a.

With the emergency valve located outside the boiler, it will be apparent that even though this valve is closed, the dry pipe in the boiler leading to the steam outlet will be subjected only to a balanced steam pressure, and for this reason a conduit formed of comparatively light sheet metal is sufficient, as its sole function is to supply dry steam to the boiler outlet.

In accordance with my invention, the usual cylindrical pipe is replaced by a trough-like sheet metal member 16 flanged along its longitudinal edges as at 17 and secured to the top of the main boiler shell by welding or other suitable methods. At its forward end, the member 16 is enlarged and the flanged end 18 is secured to the forward flue sheet 2 in any suitable manner. The enlargement at the forward end of the member 16 provides a depending pocket 19 opposite the outlet 5 in the flue sheet 2 through which communication is established directly with the saturated header 4 of the superheater, the latter being attached to the flue sheet by any form of suitable joint 20.

The member 16 extends rearwardly to a point behind the steam dome 21 and terminates in an enlarged circular portion directly below the steam dome as appears more clearly from Fig. 3. The outer edge of member 16 is secured to the main boiler shell and centrally of the steam dome the member 16 is formed with an open-ended cylindrical portion 22 which extends upward to a point near the top of the steam dome. The diameter of the cylinder 22 is proportioned so that the annular space 23 between it and the side walls of the dome is just sufficient to provide the necessary steam flow area, and it is carried upward into the steam dome as far as is possible without constricting the passage between the top thereof and the top of the steam dome to an area less than that of the space 23.

The steam dome is provided with a removable cap 24 and as will be readily apparent from Fig. 1, the arrangement of the cylinder 22 is such that an open passage of large area is provided for access to the interior of the boiler through the opening in the top of the steam dome. It will be furthermore evident that by carrying the cylinder as nearly as possible to the top of the steam dome,

the position of the steam inlet of the dry pipe passage 25 is such as to obtain the dryest steam possible.

In view of the position of the emergency valve outside the boiler, it is not essential that the joint between the boiler shell and the flanges 17 and 18 be made steam-tight, as leakage of steam into the dry pipe passage 25 through these joints is of no material consequence, but it is preferable that substantially tight joints be made in order that the entire steam supply may enter the dry pipe through the inlet placed at the maximum distance above the water line of the boiler.

It will be obvious that many changes and variations in the specific construction and arrangement of the apparatus illustrated may be made, and it is to be understood that my invention is not to be limited by the illustrative embodiment shown, but is to be limited only by the scope of the appended claims.

I claim:

1. In a locomotive, a boiler having a steam outlet, a superheater inlet header in direct communication with said outlet, emergency valve means located in said header to shut off steam flow therethrough, said means comprising a valve urged to closed position by steam flow from the boiler, manually controlled means normally holding said valve in open position, a superheater outlet header, and a throttle located in said outlet header.

2. In a locomotive, a boiler having a steam outlet, a superheater inlet header in direct communication with said outlet, emergency valve means located in said header to shut off steam flow therethrough, said means comprising a plurality of valves urged to closed position by steam flow from the boiler, manually controlled means normally holding said valves in open position, a superheater outlet header, and a throttle located in said outlet header.

3. In a locomotive, a boiler having a steam outlet, a superheater comprising inlet and outlet headers, emergency valve means located in said inlet header for controlling the steam flow therethrough, said means including a valve urged to closed position by steam flow from the boiler, manually controlled means for opening said valve, a throttle located in said outlet header, and an auxiliary valve for admitting steam to said superheater to balance said first named valve.

4. In a locomotive, a boiler having a steam outlet, a superheater inlet header, a partition dividing said header into an upper inlet chamber in direct communication with said outlet, and a lower outlet chamber, a plurality of ports in said partition, valves located in said ports, said valves being urged to closed position by gravity and by steam flow from the boiler, and manually controlled means normally holding said valves in open position.

5. In a locomotive boiler, a cylindrical

- boiler shell having a steam dome opening, a forward flue sheet having a steam outlet therein, and an inverted trough-like member secured to the upper portion of said shell around the dome opening and the outlet and forming with the shell a dry pipe connecting the steam dome and said outlet, said member having an upwardly extending cylindrical portion located in said dome and spaced from the walls thereof to form a dry pipe inlet at the top of said dome.
5. In a locomotive, a boiler having a steam dome, a dry pipe extending into said steam dome, said dry pipe comprising a cylindrical section terminating adjacent the top of said dome, said section providing a steam inlet through the interior thereof and forming with the walls of said dome an annular dry pipe passage surrounding said section.
10. In a locomotive, a steam dome, a dry pipe having an inlet end formed by an open-ended vertical cylindrical section spaced from the walls of said dome and terminating adjacent the top thereof, and a cover plate removably secured to the top of said dome above said cylindrical section, whereby access is provided to the interior of said boiler through said dome and section.
15. In a locomotive, a steam dome, a dry pipe having an inlet end formed by an open-ended vertical cylindrical section spaced from the walls of said dome and terminating adjacent the top thereof, and a cover plate removably secured to the top of said dome above said cylindrical section, whereby access is provided to the interior of said boiler through said dome and section.
20. In a locomotive, a steam dome, a dry pipe having an inlet end formed by an open-ended vertical cylindrical section spaced from the walls of said dome and terminating adjacent the top thereof, and a cover plate removably secured to the top of said dome above said cylindrical section, whereby access is provided to the interior of said boiler through said dome and section.
25. In a locomotive, a steam dome, a dry pipe having an inlet end formed by an open-ended vertical cylindrical section spaced from the walls of said dome and terminating adjacent the top thereof, and a cover plate removably secured to the top of said dome above said cylindrical section, whereby access is provided to the interior of said boiler through said dome and section.
